UNITED STATES PATENT OFFICE.

WILLIAM L. D'OLIER AND HARRY H. STEPHENS, OF PHILADELPHIA, PENNSYLVANIA.

CENTRIFUGAL APPARATUS.

1,129,178.

Specification of Letters Patent. Patented Feb. 23, 1915.

Application filed December 23, 1911. Serial No. 667,500.

To all whom it may concern:

Be it known that we, WILLIAM L. D'OLIER and HARRY H. STEPHENS, citizens of the United States, residing at Philadelphia, in the county of Philadelphia and State of Pennsylvania, have invented certain new and useful Improvements in Centrifugal Apparatus, of which the following is a specification.

Our invention relates to centrifugal apparatus, particularly centrifugal machines for the centrifugal separation of solids from liquids, liquids from liquids, etc., in fact, for centrifugal separation of any kind to which a machine of this type is adapted.

Our invention resides in a centrifugal machine which is adapted to run at particularly high speeds, considering the size of the machine, for the separation of solids or semi-solids and the like from sugar solutions, syrups, varnish, or other viscous fluids, or for any centrifugal separation where excessively high speeds are necessary, as where the material to be separated from the body of the solution is of only relatively slightly different specific gravity, or is finely divided and in suspension in the liquor.

It is one of the characteristic features of our invention that there are provided within the rotating centrifugal drum a plurality of centrifugal drums, with spaces between them, the material under treatment passing, not through these walls of the drums, but passing upwardly or downwardly over the edges thereof into the next space.

Our invention resides also in the features hereinafter described and claimed.

For an illustration of one of the forms our invention may take, reference is to be had to the accompanying drawing, in which:

Figure 1 is a vertical half sectional view, and half elevational view, of one form our machine may take. Fig. 2 is a fragmentary sectional view, on larger scale, showing part of the same sectional view of the drum or basket shown in Fig. 1. Fig. 3 is a partial horizontal sectional view taken on the line A—A of Fig. 1. Fig. 4 is a fragmentary sectional view taken on the line B—B of Fig. 1.

Referring to the drawing, a suitable support 1, itself supported upon I-beams or any other suitable support, not shown, carries the bracket or yoke member 2 through the medium of the rods 3, preferably three or

more in number, which have freedom of motion due to the spherical bearing members 4 and 5 with both the support 1 and with the bracket or yoke 2. When the centrifugal apparatus gyrates, while in operation, the same may tilt or incline slightly with respect to the support 1, due to the yielding of these supporting rods 3. Upon the upper end of the bracket or yoke 2 is secured by bolts 6 the curb 7 having the internal upturned lip or flange 8 and carrying at its top the cover 9 having the axial receiving funnel or spout 10. The rotating shaft 11 of the centrifugal apparatus has secured thereon the sleeve 12 which has a vertical ball bearing 13 and a lateral ball bearing 14 upon the member 15 carried at the lower end 16 of the yoke or bracket 2. The vertical bearing 13 carries the weight of the shaft and its attached parts, and the lateral bearing 14 takes up lateral strains in the shaft as does also the lateral ball bearing 17 intervening between the sleeve 18 upon the shaft 11 and the stationary member of the ball bearing, the latter supported by the inwardly extending arms 19 upon the yoke or bracket 2. At the lower end of the shaft 11 is secured the rotor 20 of any suitable type of motor, here shown as the rotor of a steam turbine, disposed within the stationary casing 21 supported upon the part 16 of the bracket 2 by the extension 22. Steam is led to a suitable nozzle or nozzles by a flexible hose, not shown.

In operation, the steam turbine drives the shaft 11 and gyrates with the shaft 11 in fixed relation thereto, all parts gyrating upon the swinging or supporting bolts 3. At its upper end the shaft 11 enters a bore in the bottom member 23 of the centrifugal drum or basket. The shaft 11 has a flange or ears 24 through which pass bolts 25 securing the same rigidly to the bottom member 23 for driving the same and the attached parts. The centrifugal basket or drum proper is shown at 26 and is cylindrical, and is made of materials of high tensile strength, for example, nickel-steel. The bottom member 23 is made of some such material, as cast steel or wrought iron, having a different modulus of elasticity from that of the material of the drum 26. The material of the member 23 has such a modulus of elasticity that at the high speeds employed the centrifugal forces acting upon

the member 23 cause it to expand or tend to expand to a greater extent than the expansion of the member 26, due to the centrifugal forces acting upon it. The result is that the joint 27 between members 23 and 26 closes tighter and tighter at the higher and higher speeds of rotation. The member 26 is secured by a plurality of bolts 28 to the outer flange upon the member 23, this outer flange 29 having its lower edge partially embraced by the lip or flange 30 upon the member 26. The result is that the great pressures developed within the drum prevent the shearing of the bolts 28, the strain being taken by this flange or lip 30 on the drum 26. The drum 26 has a cover 31 preferably also of high tensile strength material, such as nickel-steel, the cover 31 resting upon the top edge of the drum 26 and held thereto by the ring nut 32 screw-threaded upon the drum 26, the nut 32 being also preferably of high tensile strength material, such as nickel-steel. Across the horizontal joint between the cover 31 and the drum 26 extends a packing or gasket 33 from which a plurality of perforations through the cover 31 extend into the interior thereof, so that the fluid under high pressure within the drum exerts an outward pressure upon the material 33 to more tightly close the joint. At its inner edge the cover 31 carries the member 34 having discharge orifices 35 through which material is discharged into the relatively stationary passage or chamber 36 delivering to the discharge spout 37. The member 34 has a funnel or spout portion 38 surrounding the intake spout or funnel 10, whereby any overflow of the material just delivered into the drum passes over the edge of the funnel 38 into the chamber 39 and thence discharges through the spout 40. In the bottom of the drum is provided a mud pan 41 and on the bottom of the mud pan 41 rests a plurality of vanes 42 integral with or secured upon the member 43 forming an inner chamber. With their bottoms or lower edges resting upon the top side of the horizontal portion of the member 43 are a plurality of drums 44. Attached to the drums 44, or otherwise suitably supported, are the vanes 45 extending across the annular spaces between the drums and in the annular space between the outer drum 44 and the drum 26. The outer drum 44 has perforations 46 for allowing egress of material into the outer annular space. And the inner wall of the outer drum 44 may be covered with a sheet or layer of filter material 47. From the space within the member 43 communication to the space between the outer surface of the member 43 and the inner wall of the inner drum 44 is afforded by the holes or perforations 48. The drums 44 rest inside of lugs or ribs 49

upon the upper side of the horizontal portion of the member 43. These ribs or lugs are not circumferentially continuous, but allow a free space under the edge of alternate drums for passage of fluid from the space on one side of the drum to the space on the other side by passing around the lower edges of the drums. The other alternate drums have similar passages around their upper edges, as clearly seen in Fig. 2, the corresponding lugs or ribs 49 being provided on the member 50 engaging at its inner edge upon the vertically-faced boss 51 on the member 43, and resting upon the top edges of one or more of the drums 44. Upon the top side of the member 50 are provided a plurality of vanes 52 extending up to the under side of the cover or lid 31. The course of the fluid is indicated by the arrows in Figs. 1 and 2. The operation is as follows: The steam turbine is started by placing the same in communication with a source of steam pressure and the shaft 11 is rotated together with all parts attached thereto, including the member 23, drum 26 and the parts attached thereto and contained within the drum. The speed is particularly high for certain separations, and in the case of a drum of a diameter of 36 inches, for example, the speed is 2,000 revolutions per minute, approximately. The raw liquor is delivered into the interior of the drum through the funnel 10 into the space inside of the member 43. The vanes 42 cause the liquor to revolve with the drum with a minimum of slippage or eddying. The liquor then passes up through the perforations 48 into the space between the inner drum 44 and the outer wall of the member 43, the vanes 45 here again causing the liquor to rotate with the drum with a minimum of slippage and eddying. The liquor then passes over the top edge of the inner drum 44, see Fig. 2, into the space between the inner drum 44 and the next drum 44. The liquor then passes around the lower edge of the second drum 44 into the space between it and the next outer drum, thence over the top edge of the next outer drum 44, as indicated by the arrows in Fig. 2, into the space inside of the outer drum 44. Liquor then passes through the filtering medium 47, if employed, and thence through the perforations 46 into the space between the outer drum 44 and the inner side of the drum 26. It then passes upwardly, as indicated by the arrow in Fig. 2, over the member 50 and between the vanes 52 to the interior of the member 34 as indicated by the arrows in Fig. 1, thence through the orifices 35 into the chamber 36 and then is delivered at the discharge spout 37. The difference in head between the fluid in the funnel 10 and the fluid passing over the funnel or plate 38 is sufficient to cause the flow of fluid through the machine not- 130

withstanding the fact that in the parts of the apparatus at a greater distance from the center of the shaft, the liquid pressures are extremely high. The vanes 45 transfer 5 strains to outer drum and prevent slippage or eddying, as described above. The vanes 52 also reduce the velocity of discharge evenly and increase the discharge output.

On the inner side of the curb 7 may be 10 provided a plurality of vertically disposed rollers 53 at a plurality of points around the inner circumference of the member 7, these rollers being placed quite close to the outer surface of the drum 26 so that in case 15 of breakage of shaft 11 or severe flexure the drum will bear upon and roll upon these rollers 53.

By the construction hereinbefore described, the liquor does not flow through the 20 drums 44 in succession, but passes upwardly and downwardly in the spaces between them and over their edges into the next spaces. Furthermore, it is apparent from the hereinbefore described apparatus that the turbine 25 or motor has no bearings and that both the stationary and rotating elements of the turbine gyrate with the shaft and all attached parts.

By varying the number of drums 44, the 30 length of path of liquor flow may be made long or short to suit conditions, such as different kinds of liquors, or liquors having different amounts and natures of materials in suspension. The drums 44 may take the 35 form of cones alternately pitched with respect to the direction of flow of the liquor to aid the movement or circulation of the liquor.

What we claim is:

40 1. In combination, a centrifugal drum, an axial member forming an axial receiving chamber, one or more drums intervening between said axial member and said first named drum, and resting upon a horizontal portion of said axial member, a member extending from said axial member across the tops of said intervening drum or drums and forming closed joints therewith at their tops, and means for causing liquor to flow in 45 succession through the spaces between said drums backwardly and forwardly longitudinally of the axis of said drum.

50 2. In combination, a centrifugal drum, an inner member movable with said drum, one or more drums intervening between said inner member and said first named drum, means including a member extending across the top or tops of said intervening drum or drums, for causing liquor to pass backwardly and forwardly longitudinally of the axis of said drum through the spaces between said drums, a cover for said first named drum, a discharge passage formed between said member and said cover, and a 55 60 65 vane in said discharge passage.

3. In combination, a centrifugal drum, an inner member movable with said drum, means for delivering liquor to the inside of said member, one or more drums intervening between said inside member and said first-named drum, means for causing all the liquor to pass in succession from within said inside member backwardly and forwardly longitudinally of the axis of rotation through all the spaces between said drums, 70 vanes disposed within said inner member and said intervening drums, a cover for said intervening drums, a discharge passage above said cover, and a vane in said discharge passage. 75 80

4. In combination, a centrifugal drum, an inner member movable with said drum, means for delivering material to the inside of said member, one or more drums intervening between said inside member and said first-named drum, means for causing material to pass from within said inside member backwardly and forwardly longitudinally of the axis of rotation through the spaces between said drums, and vanes inside 90 of said inside member. 95

5. In combination, a centrifugal drum, an inner member movable with said drum, means for delivering material to the inside of said member, one or more drums intervening between said inside member and said first-named drum, means for causing material to pass from within said inside member backwardly and forwardly longitudinally of the axis of rotation through the 100 spaces between said drums, and vanes in the spaces between said drums. 105

6. In combination, a centrifugal drum, an inner member rotatable with said drum, a plurality of centrifugal drums intervening between said inside member and said first named drum, said inside member having a lower horizontal portion on which said intermediate drums rest, a top member engaging the tops of all said intermediate drums, 110 alternate intermediate drums having passages across their tops and the other intermediate drums having passages across their bottoms, said inside member having a perforation communicating with the inside of the intermediate drum of least diameter, whereby all the liquor passes between all said drums in succession, and a passage from the space between said first named drum and the outer intermediate drum communicating with the space above said top member, and a vane in the space above said top member. 115 120

7. In combination, a centrifugal drum, an inner member movable with said drum, means for delivering material to the inside of said member, one or more drums intervening between said inside member and said first-named drum, means for causing material to pass from within said inside mem- 125 130

ber backwardly and forwardly longitudinally of the axis of rotation through the spaces between said drums, members extending across the tops and bottoms of said intermediate drums, and vanes above the member extending across the tops of said drums.

8. In combination, a centrifugal drum, an inner member movable with said drum, means for delivering liquor to the inside of said member, one or more drums intervening between said inside member and said first-named drum, a vane in the space between the inner drum and said inner member, members making closed joints at the tops and bottoms of said intermediate drum or drums, said member making closed joints at the bottoms of said drums having apertures forming passages from within said inner member into the space between the same and the inner drum, means providing passages around the top and bottom edges of said drums, alternate drums having said passages at their tops, and the other drums having said passages at their bottoms, whereby all the liquor passes through all spaces in succession.

9. In combination, a centrifugal drum, means for delivering liquor into said drum, a plurality of members within said drum, means for causing the liquor to pass backwardly and forwardly longitudinally of the axis of said drum through the spaces between said members, a single discharge path

for all the liquor, and a vane in said discharge path.

10. In combination, a centrifugal drum, an inner member having a horizontally extending bottom portion, vanes on which said inner member rests, one or more drums resting upon said bottom portion, a liquor passage through said bottom portion into the space between said inner member and the next drum, and means for causing the liquor to pass in succession backwardly and forwardly through all the spaces between drums.

11. In combination, a centrifugal drum, an inner conical member increasing in diameter downwardly, vanes within said member, one or more drums intervening between said inner member and said first named drum, means for passing liquor in succession backwardly and forwardly through all the spaces between drums, and a pan beneath said inner member and said intervening drums.

In testimony whereof we have hereunto affixed our signatures at Philadelphia, Pennsylvania, this 22nd day of December, 1911, in the presence of the two subscribing witnesses.

WILLIAM L. D'OLIER.
